[57] CLAIM

The ornamental design for a poultry waterer, as shown and described.

DESCRIPTION

FIG. 1 is a perspective view of a poultry waterer showing my new design;

FIG. 2 is a top plan view thereof;

FIG. 3 is a side elevational view thereof the opposite side being a mirror image of the side shown;

FIG. 4 is a side elevational view at 90° from the side elevational of FIG. 3 the opposite side being a mirror image of the side shown; and,

FIG. 5 is a bottom plan view thereof.
